US0D1082479S

(12) **United States Design Patent** (10) **Patent No.:** **US D1,082,479 S**
(45) **Date of Patent:** **** Jul. 8, 2025**

(54) **STORAGE BOX FOR SCREWDRIVER**

(71) Applicant: **Shenzhen Fanttik Technology Innovation Co., Ltd.**, Shenzhen (CN)

(72) Inventor: **Mingkai Li**, Shenzhen (CN)

(73) Assignee: **SHENZHEN FANTTIK TECHNOLOGY INNOVATION CO., LTD.**, Shenzhen (CN)

(**) Term: **15 Years**

(21) Appl. No.: **29/882,564**

(22) Filed: **Jan. 17, 2023**

(51) LOC (15) Cl. **03-01**

(52) U.S. Cl.

USPC **D3/315**; D8/82

(58) **Field of Classification Search**

USPC D8/14, 71, 82, 85; D3/302, 905, 315, D3/201, 273; D9/432

CPC . B25H 3/00; B25H 3/02; B25H 3/026; B65D 1/22; B65D 3/10

(57) **CLAIM**

The ornamental design for a storage box for screwdriver as shown and described.

DESCRIPTION

FIG. 1 is a first perspective view of a storage box for screwdriver showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of an encircle portion 9 in FIG. 1.

The dash-dash broken lines in the Figures are for the purpose of illustrating portions of the article that form no part of the claimed design.

The dot-dash broken lines are for the purpose of illustrating the boundary of corresponding views and form no part of the claimed design.

1 Claim, 9 Drawing Sheets
